AUTOMATIC VOLUME CONTROL CIRCUITS

George L. Beers, Collingswood, N. J., assignor to
Radio Corporation of America, a corporation
of Delaware

Application December 19, 1933, Serial No. 703,034

17 Claims. (Cl. 250—20)

My present invention relates to amplifier control arrangements, and more particularly to improved automatic volume control systems for radio receivers.

Automatic volume control arrangements employed in the past have utilized gain control devices wherein a volume control rectifier output electrode assumed increasingly greater negative potentials as the signal input to the receiver increased. It is one of the main objects of this invention to provide an automatic volume control arrangement wherein precisely the reverse action takes place, the control rectifier output electrode swinging more positive with respect to the controlled amplifier cathode as the signal input to the rectifier increases.

Another important object of the invention is to provide an automatic volume control arrangement of the type utilizing a diode rectifier to develop a direct current potential component from signals, the component being employed, however, to regulate the potential of the input grid of a tube which does not itself operate as a detector, rectifier or signal amplifier, the gain of the high frequency amplifier to be controlled being regulated in accordance with variations in plate current flow of the last named tube.

Another important object of the invention is to provide improved automatic volume control arrangements wherein the plate potential for the volume control tube can be supplied from an alternating potential source.

An additional object of my invention is to provide improved automatic volume control arrangements of the type wherein the volume control tube has an alternating potential applied to its plate and the alternating current circuits already existing in the receiver are utilized to provide this plate potential, whereby a separate plate potential source for the volume control tube is not required in either direct or alternating-current operated receivers.

Another object of the invention is to provide an automatic volume control tube for a receiver wherein an alternating potential can be applied to the control tube plate, the potential being derived from the oscillator circuit when the receiver is of the battery-operated, superheterodyne type, and from the conventional power supply transformer when the receiver is alternating-current operated.

An additional object of the invention is to provide an automatic volume control system wherein the amplified signal voltage may be used as plate potential for the volume control tube.

Still another object of the invention is to improve the existing and well-known types of automatic volume control arrangements for radio receivers, and particularly to provide satisfactory and economical arrangements of the type wherein an alternating potential may be applied to the automatic volume control tube.

The novel features which I believe to be characteristic of my invention are set forth in particularity in the appended claims. The invention itself, however, both as to its organization and method of operation, will best be understood by reference to the following description, taken in connection with the drawings, in which I have indicated diagrammatically several circuit organizations whereby my invention may be carried into effect.

In the drawings:—

Fig. 1 shows one arrangement embodying the invention,

Fig. 2 shows a modification employing alternating current on the control tube plate,

Fig. 3 shows a modification of the arrangement of Fig. 2,

Fig. 4 illustrates a modification employed in a battery-operated superheterodyne receiver,

Fig. 5 shows a further modification of the invention,

Fig. 6 illustrates still another modification.

Referring now to the accompanying drawings, wherein like reference characters in the different figures represent similar circuit elements, there is shown in Fig. 1 a conventional radio receiving system which embodies the automatic volume control network of the present invention. The amplifier tube 1 is disposed in a stage of tuned radio frequency amplification, and it is to be clearly understood that this amplifier stage may be the intermediate frequency amplifier of a superheterodyne receiver, or one of the tuned radio frequency amplifier stages of a cascaded tunable radio frequency amplifier receiver. The reference numeral 2 designates the source of signals which is coupled, as at M_1 , to the tuned input circuit 3 of the amplifier tube 1. Of course, if the receiver is of the superheterodyne type then the network 2 will be understood to comprise the conventional networks which precede the intermediate frequency amplifier, and these commonly are a radio frequency amplifier coupled to a signal collector, and a first detector circuit and oscillator. If the receiver is of the tuned radio frequency type, then the reference numeral 2 will designate the signal collector, or one or

more preceding stages of tuned radio frequency amplification.

Assuming that the receiver is of the superheterodyne type, the resonant circuit 3 is fixedly 5 tuned to the operating intermediate frequency. The coupling transformer M_2 in that case has its primary and secondary circuits each tuned to the operating intermediate frequency, while the detector tube, the second detector in the 10 case of the superheterodyne receiver, is connected across the tuned circuit 4. In Fig. 1 the detector tube is shown as a diode 5, and the cold electrode, or anode, thereof is connected to the cathode through a path which includes the 15 tuned circuit 4 and a resistor 6 arranged in series, the resistor 6 being shunted by a radio frequency by-pass condenser 7.

The signal current impressed upon the circuit 20 4 develops across the resistor 6 an audio frequency signal potential component and a direct current potential component. The path which includes lead 8 and audio frequency signal coupling condenser 9 transmits the audio frequency signal component to one or more stages of audio 25 frequency amplification, and the amplified audio frequency signal energy may then be reproduced in any desired manner. The lead 8 may terminate in an adjustable tap 10, and this tap 30 may function as the manual volume control element of the receiver if desired. The direct current potential component of the detected signal current is impressed upon the control grid 11 of a screen grid tube 12 by connecting the grid 11 through a lead 13 to the positive potential side 35 of resistor 6. A potentiometer resistance P furnishes the operating direct current voltages for the electrodes of tubes 1, 5 and 12, and only these circuits are shown in detail because they 40 are the only ones that need be described for a clear understanding of the invention. It is to be clearly understood that the resistor P is connected to the direct current power supply source, and that the latter may comprise any arrangement well known to those skilled in the broadcast receiver art.

The anode of diode 5 is connected to a point 45 14 on resistor P which is negative with respect to the point 15 to which the cathode of tube 12 is connected. The screen grid and anode of tube 12 are connected to points of more positive 50 potential than the point 15, a resistor R connecting the anode of tube 12 to the point 16. The cathode of amplifier tube 1 is connected by lead 17 to point 18 on the potentiometer P , and a lead 19 connects the anode of tube 1 to point 55 20 which is at a more positive potential than the point 18. The control grid of amplifier tube 1 is connected through a path which includes the lead 21 and resistor 22 to the anode side of 60 resistor R . By-pass condensers are connected from either side of resistor 22 to point 18 of the resistor P .

The circuit relations between the various elements of the system shown in Fig. 1, and the 65 functions of the elements in the operation of the system will now be described. The direct current potential drop across resistor 6 is impressed upon the control grid 11 of tube 12. The cathode of tube 12, connected to point 15 on resistor P , is at a potential which is sufficiently positive 70 with respect to the point 14 to bias the tube 12 to, or beyond, the point of plate current cut-off in order to give the desired delayed automatic volume control action. The resistor R is included in the plate circuit of tube 12, and con-

nected to point 16 on the receiver B supply system, and this point is sufficiently positive with respect to the point 15 to give the desired plate voltage.

The cathodes of the controlled tubes, and specifically the cathode of tube 1, are connected to point 18 on the potential supply resistor P , the direct current potential drop between the points 16 and 18 being utilized to provide the normal fixed bias for the controlled amplifier tubes. A 10 resistance-condenser filter 22, 23, is provided between the plate side of resistor R and the controlled amplifier grid, or grids, to eliminate any audio frequency potentials which may appear in the plate circuit of tube 12.

When a signal is received the cathode of diode 5 becomes more positive with respect to the cathode of tube 12, and the grid bias of tube 12 is, therefore, reduced thereby causing an increase in the plate current flowing through resistor R . This results in an increase in the bias on the grids of the controlled amplifier tubes. When no signals are received the negative bias on the grid 11 of tube 12 is a maximum, and, therefore, there is a decreased flow of plate current through the resistor R , and the controlled amplifiers are operated at maximum sensitivity.

In Fig. 2 there is shown the circuit arrangement of Fig. 1 modified in various respects. It will be noted that the cathode of tube 12 connects directly to the anode of the diode detector tube 5 through a lead 5'. The resistor 6 is connected to a point 14' on the potential supply resistor P which is more negative than the point 14 to which the anode diode is connected. The control grid 11 of tube 12 is connected to an intermediate point 6' on resistor 6. This arrangement results in a positive bias being applied to the anode of tube 5, and a negative bias being impressed on the grid 11 of tube 12.

If the resistance between the cathode side of resistor 6 and point 6' is equal to the resistance between point 6' and point 14', the bias on the control grid 11 will be approximately half the potential drop between points 14' and 14. The 40 change in the control grid bias of tube 12 with an increase in the strength of the signal applied to diode 5 will be approximately half that obtained from the arrangement shown in Fig. 1. The resistor R in the plate circuit of tube 12 in Fig. 2 returns directly to the cathode of the tube, the plate potential for the tube being provided through the secondary winding of the 60 cycle alternating current transformer M_3 . The use of the alternating current plate potential for tube 12 makes it unnecessary to provide the plate potential for this tube from the V supply system of the receiver. Since the plate supply for the automatic volume control system and the amplifier tubes must normally be connected in series, the use of alternating current on the plate of tube 12 makes it possible to reduce the total potential which the receiver B supply system must provide by the voltage normally used for tube 12. The screen grid of tube 12 can, of course, connect to the B supply system in parallel with the screen grids of the other amplifier tubes.

The resistance-condenser filter 13'-12', inserted between point 6' and the input electrodes of tube 12 in Fig. 2, functions to prevent audio frequency potentials being applied to the control grid of tube 12. This filter can likewise be employed in the arrangement shown in Fig. 1. While the diode 5 in Fig. 1 is shown as functioning additionally as the second detector of the re-

ceiver, in Fig. 1 a separate audio detector must be used because of the positive bias which is applied to the anode of the diode tube 5. For this reason the conventional detector shown in Fig. 2 is illustrated as being coupled through a signal path to the input network of the diode 5, the demodulated output of the detector being impressed upon the succeeding audio frequency amplifier network through the coupling condenser 8'.

10 It is within the scope of the present invention to combine the detector shown in Fig. 2 in the same tube envelope as the electrodes of the automatic volume control diode 5. Those skilled in the art are well aware of multi-function tubes which can accomplish this purpose, and it is pointed out that a common cathode could then be used for the two diode anodes, one of the diode anodes functioning for the automatic volume control system as in Fig. 2, and the other diode 20 anode functioning as the audio demodulator as shown in Fig. 1. The advantages of the arrangement shown are as follows:—

25 In Fig. 2 the anode of the rectifier 5 which is coupled to the output of the amplifier connects directly to the cathode of the tube 12. In both arrangements the output electrode of the rectifier becomes less negative with respect to the cathode of the tube or tubes which the rectifier controls as the signal strength increases. This is distinctly contrary to automatic volume control methods employed heretofore wherein the output electrode of the automatic volume control rectifier becomes more negative with increase in signal strength with respect to the controlled amplifier cathodes.

30 35 The plate potential for the tube 12 in both arrangements can be supplied from an alternating current source, and thereby minimize the voltage requirements of the receiver B supply system. Either arrangement provides a large change in control grid bias on the controlled amplifier tubes for a small increase in signal strength due to the high direct current component amplification provided by tube 12. In a previous automatic volume control system, in which the plate potential of a triode was supplied from an alternating current source and the signal was applied to the control grid, difficulty was encountered when a signal was received which was modulated 100% with 60 cycles and the modulation was 180 degrees out of phase with the applied plate voltage. Under these conditions no automatic volume control action was obtained. With the present arrangements this difficulty is overcome since only variations in the direct current potential derived from the control diode are applied to the control grid of the tube which is supplied with the alternating current plate potential.

40 45 50 55 In Figs. 3 and 4 are shown two further modifications of the present invention, both of these modifications utilizing the essential mode of operation disclosed in Fig. 2. The alternating current potential utilized for the plate of tube 12 in Fig. 2 may be developed by the local oscillator of the superheterodyne receiver, or it may be derived from another source such as the power transformer in an alternating current operated receiver. In Fig. 3 the plate potential of tube 12 is supplied from the secondary 30 of the power 50 transformer T through the coupling condenser 31. The transformer T is of a conventional and well known form, and its primary winding is connected to the usual 60 cycle alternating current source. The secondary winding 30 is connected to the usual full wave power rectifier,

the mid-tap of the secondary winding being connected to the negative side of the bleeder resistor P. Only such details of the power supply circuit arrangement as are essential to an understanding of the present invention are shown, the remaining details being well understood by those skilled in the art.

5 10 15 20 25 30 35 40 45 50 55 60 65 70 75 In Fig. 2 the plate potential for tube 12 is supplied through a special winding on the power transformer, the special winding being connected in series with the plate of the tube. However, in Fig. 3 the secondary winding of the power transformer itself is utilized for supplying the potential for plate 12, the alternating current potential being applied through the condenser 31. The diode control tube 5 has its anode connected to point 14, the diode functioning not only as a control rectifier for the automatic volume control system, but also as the audio demodulator, and its circuits are arranged as shown in Fig. 1. The anode of tube 12 is connected through the resistor R to point 16' on the bleeder resistor P, and it will be noted that this point is more negative than the point 15 to which the cathode of tube 12 is connected. It should also be noted that the cathode of the controlled amplifier is connected by lead 40 directly to the cathode of tube 12. The actual electrodes of the controlled amplifier stage have been omitted, and only the direct current connections from the bleeder resistor P and the tube 12 are shown. This same connection arrangement may be employed in connection with Fig. 2 wherein the alternating current plate potential is provided by the series winding arrangement. The resistor R in the plate circuit of tube 12 is connected to point 16' which is more negative than point 15 because there is thus provided the proper fixed bias on the controlled amplifier tube since the cathodes of the tube 12 and the controlled amplifier tube 40 are connected to the common point 15.

75 The tube 12 is a screen grid tube, the screen being connected to point 41 on the bleeder resistor P, and preferably is of the pentode type. If the plate potential for tube 12 is supplied from the local oscillator of the receiver, the applied plate potential may vary through the tuning range of the receiver, or with variations in tubes, etc. Since the operating characteristics of the pentode tubes are reasonably independent of the applied plate potential, the effects of these variations will not be serious. Of course, a pentode tube may also be utilized for the tube 12 in Fig. 2.

80 85 90 95 100 In Fig. 6 there is shown a variation of the arrangement shown in Fig. 3, and it will be noted that the difference between the two arrangements resides in the fact that in Fig. 6 both the cathodes and control grids of the amplifier tubes being controlled are connected to the bleeder resistor P' so that they are always negative with respect to any of the rectifier electrodes. This is permitted through the use of the alternating potential on the plate of the automatic volume control tube. Since the circuit elements in Fig. 6 are substantially the same as those shown in Fig. 3, similar reference numerals are utilized, but in Fig. 6 these reference numerals are associated with prime designations. It will be observed that the control grid 11' of the volume control tube 12' is connected to the cathode side of resistor 6', while the negative side of resistor 8' is connected to point 16' on the bleeder resistor P'. Furthermore, it will be noted that in the arrangement of Fig. 6 the diode anode is 75

connected to the high alternating current potential side of the tuned input circuit of diode 5', while the cathode of the diode is connected to the control grid side of resistor 6'. The resistor R' is connected between the anode of tube 12' and point 16', which is now at a more negative potential than the point 14'. Additionally, the lead 40', instead of being connected to the cathode point 15', is connected to a point 16' which is at a potential intermediate the potentials of points 16' and 14'.

The arrangement of Fig. 4 shows the same general arrangement of Fig. 3 applied to a battery operated receiver. The diode 5 must be provided with an indirectly heated cathode, and all the other tubes in the receiver may be of the filament type and can be operated from a common source of filament potential. The plate potential for tube 12 is supplied through coupling condenser 50 from the tunable circuit 51 of the local oscillator. In other words, it is to be clearly understood that the receiver shown in Fig. 4 is of the superheterodyne type, and that the circuit 51 is connected in the local oscillator stage 26 of the receiver.

The details of the local oscillator stage are not included, because they are not essential to a proper understanding of the present invention, one side of the circuit 51 being shown grounded, 30 and the high alternating current potential side being shown connected through condenser 50 to the plate of tube 12.

The variable condenser 52 functions as the tuning means of the local oscillator stage, and 35 those skilled in the art are well aware of the manner of constructing a receiver of this type. By means of the arrangement shown in Fig. 4 a battery operated receiver can be equipped with an amplified automatic volume control system 40 which does not require the use of an additional source of plate potential. It is believed that the remaining constructional details of Fig. 4 will be readily understood from the arrangement shown in Fig. 3. The diode 5 functions both as a control 45 rectifier and as an audio demodulator, the anode of diode 5 being connected to the negative terminal of the biasing source C, and the cathode of tube 12 being connected to the positive terminal of the C bias source.

50 The volume control resistor R is connected between the plate of tube 12 and the plate of the diode 5, the grid of the controlled radio frequency amplifier being connected to the plate side of resistor R. The resistance-condenser 55 filter 22', 23' is employed to prevent audio frequency pulsations from affecting the controlled amplifier, and is disposed in the automatic volume control arrangement. Tubes 5 and 12, both in Figs. 3 and 4, can be combined in a single tube 60 envelope if desired. Additionally, a small copper oxide rectifier may be substituted for the rectifier 5 in either of Figs. 3 or 4.

In Fig. 5 is shown a modification of the present invention which is based upon a combination of 65 the arrangement shown in Figs. 1 and 3. In this form of the invention the alternating potential for the automatic volume control tube is provided by the received signal. The tube 60 has its grid circuit coupled to the grid of tube 1 70 through a small signal coupling condenser 61. The received signal is amplified by tube 60, and applied to the plate of the automatic volume control tube 12 through the coupling transformer M4. In case sufficient voltage is not developed across 75 the oscillator tuned circuit in some battery oper-

ated receivers, the arrangement shown in Fig. 5 may be used to advantage.

In any of the automatic volume control arrangements shown herein the determining factor in the plate potential which is required for the 5 volume control tube is the amount of bias which will be necessary to provide sufficient control for the strongest signal which the receiver must handle. With the arrangement shown in Fig. 5 the plate potential for the volume control tube 10 12 automatically increases as the signal increases so the necessary plate potential is always available to provide the required bias voltage. This is accomplished specifically by connecting the plate of tube 12, as through a lead 62, to one side of 151 the secondary winding 63 of transformer M4, the opposite side of winding 63 being connected by lead 64 to the negative side of resistor R. It will be noted that the reference numerals employed in Figs. 1 and 3 are employed in Fig. 5 202 and this is done because such similarly designated elements correspond to circuit elements of these figures.

While I have indicated and described several 253 systems for carrying my invention into effect, it will be apparent to one skilled in the art that my invention is by no means limited to the particular organizations shown and described, but that many modifications may be made without departing from the scope of my invention, as set 303 forth in the appended claims.

What I claim is:—

1. In a radio receiving system, a signal-responsive device for deriving unidirectional potentials proportional to the amplitude of received signals, an alternating potential source, means for deriving unidirectional biasing potentials directly from said alternating potential source, and connections between said device and deriving means of such polarity that the said 350 biasing potential deriving means is controlled by the potentials derived from the signal-responsive device in a sense to increase said biasing potentials when the received signal amplitude increases.

2. In a radio receiving system, a high frequency potential source, a low frequency potential source, a device for deriving unidirectional potentials from said first-mentioned source, means for deriving unidirectional biasing potentials from said low frequency source, and connections between said source and deriving means of such polarity that the amplitude of the second-mentioned unidirectional potentials is controlled by the first-mentioned unidirectional potentials in a sense to increase the biasing potential amplitude with increase of high frequency potential.

3. In a radio receiving system, an amplifier tube, a diode coupled to said amplifier tube, an 60 automatic volume control tube having an input electrode, a cathode and an output electrode, a unidirectional potential source, a direct current connection between the cathode electrode of the diode and the input electrode of the automatic 65 volume control tube, connections to said unidirectional potential source whereby the cathode of the automatic volume control tube is normally maintained at a positive potential with respect to the cathode electrode of the diode, means for 70 connecting the amplifier cathode to a potential point on said source which is positive with respect to the diode cathode potential and which is at least as positive as the control tube cathode whereby when an incoming signal is impressed. 75

upon the diode, the cathode of the amplifier tube becomes more positive with respect to the cathode electrode of the diode, and a separate potential source for supplying plate potential to the 5 automatic volume control tube.

4. In combination, a controlled amplifier, a diode demodulator having a signal input circuit connected between its cathode and anode, an impedance in the space current path of the diode 10 circuit including a relatively fixed direct current potential point, a second point on said impedance in the demodulator circuit which is at a direct current potential adapted to increase positively with respect to the first point as the intensity 15 of signals impressed on the demodulator circuit increases, said impedance being in a series path with the diode electrodes and said signal input circuit, and means connecting said second point to the input circuit of the controlled amplifier in such a manner that the gain of the controlled amplifier decreases with said signal intensity increase, said last named means including a tube having its control grid connected to 20 said second named point and its anode connected to the amplifier input circuit through a direct current connection, the cathode of the last tube being at a positive potential with respect to the potential of the said second point.

5. In combination, a controlled amplifier, a diode demodulator circuit including a resistor in its space current path, the resistor having a relatively fixed direct current potential point, a second point on the resistor in the demodulator circuit which is at a direct current potential 30 adapted to increase positively with respect to the first point as the intensity of signals impressed on the demodulator circuit increases, said demodulator circuit having a signal input network, and the resistor being in a series path with the network and diode electrodes, and means connecting said second point to the input circuit of the controlled amplifier in such a manner that the gain of the controlled amplifier decreases with said signal intensity increase.

45 6. In combination, a controlled amplifier, a demodulator circuit including an impedance in its space current path having a relatively fixed direct current potential point, a second point on the impedance in the demodulator circuit which is at a direct current potential adapted to increase positively with respect to the first point as the intensity of signals impressed on the demodulator circuit increases, and means connecting said second point to the input circuit of the controlled amplifier in such a manner that the gain of the controlled amplifier decreases with said signal intensity increase, said last named means including an electron discharge 50 tube, additional means for impressing an alternating current between the anode and cathode of said tube, and means responsive to potential variations of the second point for varying the space current flow of said last tube.

7. In an automatic volume control system for a radio receiver, a diode rectifier having a signal input circuit connected in series between the diode cathode and anode, a controlled high frequency amplifier having its output circuit coupled to said rectifier input circuit, a control tube, 65 means for connecting the control grid of said control tube to the cathode side of said rectifier input circuit which is adapted to increase in a positive direction in direct current potential as signals are impressed upon said demodulator circuit, and a direct current connection between the 70

anode of said control tube and an input electrode of said controlled amplifier.

8. In an automatic volume control system for a radio receiver, a diode demodulator circuit, a controlled high frequency amplifier having its output circuit coupled to said demodulator circuit, a control tube, means for connecting the control grid of said control tube to a point in said demodulator circuit which is adapted to increase in a positive direction in direct current potential as signals are impressed upon said demodulator circuit, a direct current connection between the anode of said control tube and an input electrode of said controlled amplifier, and a source of alternating current potential coupled to the anode circuit of said control tube for rectification, an impedance in the control tube anode circuit developing an amplifier gain control bias from the rectified current.

9. In an automatic volume control system for a radio receiver, a diode demodulator circuit, a controlled high frequency amplifier having its output circuit coupled to said demodulator circuit, a control tube, means for connecting the control grid of said control tube to a point in said demodulator circuit which is adapted to increase in a positive direction in direct current potential as signals are impressed upon said demodulator circuit, and a direct current connection between the anode of said control tube and an input electrode of said controlled amplifier, a source of alternating current potential including a power supply transformer, means for coupling the anode circuit of said control tube to the transformer secondary winding.

10. In an automatic volume control system for a radio receiver, a diode rectifier circuit, a controlled high frequency amplifier having its output circuit coupled to said rectifier circuit, a control tube, means for connecting the control grid of said control tube to a point in said rectifier circuit which is adapted to increase in a positive direction in direct current potential as signals are impressed upon said rectifier circuit, and a direct current connection between the anode of said control tube and an input electrode of said controlled amplifier, a local oscillator circuit included in said receiver, and an oscillation coupling path between the anode circuit of said control tube and said local oscillator circuit.

11. In a radio receiver, a high frequency amplifier, a diode rectifier, a gain control tube, a resistor connected between the anode and cathode of the rectifier, a signal circuit having its high alternating current potential side connected to the diode cathode and its low alternating current potential side connected to the diode anode through said resistor, means for connecting the control grid of the gain control tube to the cathode side of said resistor, a direct current connection between the anode of the gain control tube and the input circuit of said high frequency amplifier, and a direct current potential source connected to the electrodes of said diode rectifier and gain control tube.

12. In a radio receiver, a high frequency amplifier, a diode rectifier, a gain control tube, a resistor connected between the anode and cathode of the rectifier, a signal circuit having its high alternating current potential side connected to the diode cathode and its low alternating current potential side connected to the diode anode through said resistor, means for connecting the control grid of the gain control tube to the cathode side of said resistor, a direct current con- 75

nection between the anode of the gain control tube and the input circuit of said high frequency amplifier, a direct current potential source connected to electrodes of said diode rectifier and 5 gain control tube, and a source of alternating current potential coupled to the anode circuit of said gain control tube for rectification of the alternating current, the intensity of the rectified current being dependent upon the potential 10 value of the cathode side of said resistor.

13. In a signalling system, in combination, a vacuum tube amplifier having a cathode and a control electrode, a vacuum tube detector coupled directly to the output of said amplifier, said detector having a cathode and an anode, means for 15 normally maintaining said detector cathode at a negative potential with respect to said amplifier cathode, means for normally maintaining the detector anode at a negative potential with respect 20 to said amplifier cathode, means whereby an incoming signal causes said detector cathode to become more positive, a source of alternating current energy, a rectifier for said energy, a connection between the detector cathode and an 25 electrode of the rectifier for regulating its conductivity, and a connection between said rectifier and the control electrode of said vacuum tube amplifier for impressing rectified energy upon the latter.

14. In a signalling system, in combination, a vacuum tube amplifier having a cathode and a control electrode, a vacuum tube detector coupled directly to the output of said amplifier, said detector having a cathode and an anode, means for 30 normally maintaining said detector cathode at a negative potential with respect to said amplifier cathode, means for normally maintaining the detector anode at a negative potential with respect 35 to said amplifier cathode, means whereby an incoming signal causes said detector cathode to become more positive, a source of alternating current energy, a rectifier for said energy, a connection between the detector cathode and an electrode of the rectifier for regulating its conductivity, and a connection between said recti- 40

45

45

5. rectifier and the control electrode of said vacuum tube amplifier for impressing rectifier energy upon the latter and said alternating current source comprising the 60 cycle power supply source of the system.

15. In a signalling system, in combination, a vacuum tube amplifier having a cathode and a control electrode, a vacuum tube detector coupled directly to the output of said amplifier, said detector having a cathode and an anode, means for 10 normally maintaining said detector cathode at a negative potential with respect to said amplifier cathode, means for normally maintaining the detector anode at a negative potential with respect 15 to said amplifier cathode, means whereby an incoming signal causes said detector cathode to become more positive, a source of alternating current energy, a rectifier for said energy, a connection between the detector cathode and an electrode of the rectifier for regulating its 20 conductivity, and a connection between said rectifier and the control electrode of said vacuum tube amplifier for impressing rectified energy upon the latter, and said alternating source comprising a network coupled to said amplifier.

25

16. In combination with a high frequency signal transmission tube, an oscillator arranged to produce electrical wave energy, a rectifier connected to said oscillator to produce a direct current voltage component solely from said electrical 30 waves, means for impressing the said component upon the tube to control the gain thereof, and means for controlling the efficiency of rectification of said waves by said rectifier in response to received signal amplitude variations.

35

17. A method of controlling the gain of a signal transmission tube coupled to a demodulator which consists in producing local oscillation wave energy, rectifying solely the said energy, regulating the rectification of said energy in response to 40 received signal amplitude variations, and impressing solely the rectified wave energy upon the transmission tube to regulate the gain thereof.
